Ch. Parker

Attorney

UNITED STATES PATENT OFFICE.

HAROLD H. HALLENBECK AND LEE D. BROWN, OF GREENPORT, NEW YORK.

BRUSH GATHERER.

Application filed May 16, 1925. Serial No. 30,794.

To all whom it may concern:

Be it known that we, HAROLD H. HALLENBECK and LEE D. BROWN, citizens of the United States, residing in the town of Greenport, in the county of Columbia and State of New York, have invented certain new and useful Improvements in Brush Gatherers, of which the following is a specification.

10 This invention relates to brush gatherers and more particularly to a gathering attachment for tractors.

An important object of the invention is to provide a gathering attachment particularly adapted for use in gathering the cuttings in orchards after the trees have been trimmed.

20 A further object is to provide a novel form of supporting means whereby the gathering attachment may be carried by a tractor or the like.

A further object is to provide a device of the above mentioned character provided with means for effectually gathering large 25 quantities of brush, the attachment being adapted to move upwardly or downwardly at its forward end to accommodate itself to unevenness as on the surface of the ground.

30 A further object is to provide attaching means whereby the attachment is adapted to partake of limited transverse movement when the arms thereof come in contact with stones or the like.

Other objects and advantages of the invention will become apparent during the course of the following description.

In the drawings I have shown one embodiment of the invention. In this showing:

40 Figure 1 is a plan view of the attachment in place on a tractor,

Figure 2 is a side elevation of the same, and,

45 Figure 3 is a perspective view of the gathering attachment.

Referring to the drawings, the numeral 10 designates a tractor of any ordinary construction having front and rear axles 11 and 12 respectively. The front axle is provided with the usual steering wheels 13 while the rear axle is provided with traction 50 wheels or other traction elements 14.

The attachment forming the subject matter of the present invention comprises a pair 55 of arms 15 which contact at their rear ends and diverge outwardly at their forward

ends as shown. A block 16 is secured to the rear ends of the arms 15 and is provided with a central aperture 17 for a purpose to be described. The forward ends of the arms 15 are tapered as at 18 at their sides and are curved at their bottom portions as at 19 whereby they terminate substantially in a point 20.

A cross arm 21 is secured to the arms 15 intermediate their ends, as clearly shown in Figures 1 and 3. The cross arm is provided with eyelets 22 for a purpose to be described. The cross arm is provided at opposite ends with relatively short arms 23 which are secured against the upper face of the cross arm, as shown. The arms 23 are preferably provided with substantially pointed forward ends 24. The cross arm is further provided with similar relatively short arms 25 arranged intermediate the arms 15 and 23 and secured against the lower face of the cross arm 21, as shown. The arms 25 are also tapered substantially to points 26 at their forward ends, the lower faces of the arms being curved downwardly and forwardly as at 27.

Means are provided for properly attaching the gathering attachment just described to an ordinary tractor. The block 16 is adapted to be arranged adjacent the central portion of the axle housing 12 and a bolt 27 passes through a portion of the axle housing and through the aperture 17 to pivotally support the rear ends of the arms 15. The bolt 27 is provided with a nut 28 and preferably loosely fits within the aperture 17 to permit slight vertical movement of the forward end of the attachment as well as a swinging movement in a horizontal plane. 95 Claims 29 are connected at their rear and upper ends to the front axle 11 as at 30. The forward and lower ends of the chains are crossed as shown in Figure 1 and are secured to the eyes 22, as shown in Figure 1. 100

The operation of the device is as follows:

When the trees of an orchard are trimmed, the cuttings are permitted to fall downwardly to the ground where they remain until the trimming of the orchard has been completed. The gathering attachment is then mounted on a tractor as previously described, and the tractor is operated between the rows of trees as will be apparent. The forward curved portions 19 of the arms 15 are adapted to contact with the ground to slide thereover while the arms 25 will be 105 110

slightly spaced above the ground. It will be apparent that if the forward ends of the arms 15 contact with any raised portions of the ground, the arms will be lifted slightly 5 to allow the arms to slide over the obstructions. This is also true of the arms 25, the curved portions 27 permitting these arms to ride upwardly over the obstructions. Owing to the loose connection between the 10 bolt 27 and block 16, the arms 15 may partake of lateral movement within relatively small limits. Accordingly if the forward ends of the arms 15 contact with a stone or the like the arms may swing slightly to one 15 side or the other to permit the forward ends of the arms to pass the obstructions. The chains 29, however, are adapted to prevent the arms 15 from contacting with the wheels. The arrangement of the arms 23 and 25 20 above and below the cross arm 21 provides more effectual engagement with the brush, preventing the latter from sliding rearwardly or laterally from the attachment.

It is to be understood that the form of 25 our invention herewith shown and described may be taken as a preferred example of the same and that various changes in the shape, size and arrangement of parts may be resorted to without departing from the spirit 30 of the invention or the scope of the subjoined claims.

Having described our invention, we claim:

1. A brush gatherer comprising a pair of 35 forwardly diverging arms connected together at their rear ends, means for loosely supporting the rear ends of said arms beneath the rear end of a tractor, and means for loosely connecting said arms intermediate their ends to the forward end of the tractor, the forward ends of said arms projecting a material distance forwardly of the tractor.

2. A brush gatherer comprising a pair of 40 forwardly diverging arms connected together at their rear ends, means for loosely supporting the rear ends of said arms beneath the rear end of a tractor, and means for loosely connecting said arms intermediate their ends to the forward end of the tractor, the forward ends of said arms projecting a material distance forwardly of the 45 tractor.

tractor and being adapted to rest upon the ground, the under sides of said arms being curved upwardly adjacent their forward ends and terminating in pointed forward 55 ends.

3. A brush gatherer comprising a pair of 60 forwardly diverging arms adapted to be arranged beneath a tractor, a block carried by the rear ends of said arms and provided with an aperture, a bolt carried by said tractor and loosely engaging within said aperture, and means for loosely connecting said arms intermediate their ends to the forward end of the tractor, the forward ends of 65 said arms projecting a material distance forwardly of the tractor.

4. A device constructed in accordance 70 with claim 3 wherein the means for loosely connecting said arms to the forward end of the tractor comprises a pair of crossed flexible elements connected at one end to the front axle of the tractor and at the opposite end to said arms.

5. A brush gatherer comprising a pair of 75 forwardly diverging arms, means for loosely connecting said arms to the front and rear axles of a tractor, the forward ends of said arms projecting a material distance forwardly beyond the tractor, a cross arm secured to said arms and extending outwardly therebeyond, and a plurality of relatively short arms secured to said cross arm and projecting forwardly thereof, said relatively short arms being connected to said cross arm 80 outwardly of said forwardly diverging arm.

6. A device constructed in accordance 85 with claim 5 wherein the means for loosely connecting said first named arms to the front axle of the tractor comprises a pair of crossed chains connected at one end to the axle and at the opposite end to said cross arm.

7. A device constructed in accordance 90 with claim 5 wherein certain of said relatively short arms are arranged above said cross arm, the others of said relatively short arms being arranged below said cross arm.

In testimony whereof we affix our signatures.

HAROLD H. HALLENBECK.
LEE D. BROWN.
